UNITED STATES PATENT OFFICE.

WILLIAM M. PARKER, OF OKLAHOMA, OKLAHOMA, ASSIGNOR, BY MESNE ASSIGNMENTS,
TO PARKER PROCESS COMPANY, A CORPORATION OF DELAWARE.

PROCESS FOR REFINING OILS.

1,226,990.

Specification of Letters Patent. Patented May 22, 1917.

Application filed April 4, 1916. Serial No. 88,922.

To all whom it may concern:

Be it known that I, WILLIAM M. PARKER, a citizen of the United States, residing at Oklahoma City, in the county of Oklahoma 5 and State of Oklahoma, have invented certain new and useful Improvements in Processes for Refining Oil, of which the following is a specification.

This invention relates to a process of refining oils and more particularly to a process of refining or treating crude petroleum or oil distillates for the purpose of obtaining one or more lighter oils therefrom.

One of the objects of the present invention 15 is to provide a simple and practical process for refining oil which will be substantially continuous in its operation. Another object is to provide an efficient and inexpensive process of treating or refining crude oil 20 which will divide the oil into lighter oils of more uniform quality and of larger percentage in quantity than are obtained by processes now in general use.

Other objects will be in part obvious from 25 the annexed drawings and in part indicated in connection therewith by the following analysis of this invention.

This invention accordingly consists in the several steps and the relation of each step 30 to each of the several others, both individually and in combination, all as more completely outlined herein.

To enable others skilled in the art so 35 fully to comprehend the underlying features thereof that they may embody the same by the numerous modifications and relations contemplated by this invention, drawings depicting a preferred form of the apparatus by which the process may be carried out 40 have been annexed as a part of this disclosure, and in such drawings

Figure 1 illustrates diagrammatically the first half of an apparatus which may be used in carrying out the present process;

45 Fig. 1^a is a similar view showing the last half of the same apparatus;

Fig. 2 is an enlarged view of a portion of the apparatus shown in Fig. 1 and,

Fig. 3 an enlarged view of the injector for 50 the injection of superheated steam into the oil conduit.

In order that a clearer perception of the present invention may be had and the objects sought to be obtained thereby, it may

be stated in brief that the present process 55 breaks down the heavier oils into one or more lighter oils by subjecting said heavy oils to a series of high temperatures and pressures and passing them through the apparatus at a relatively high rate of speed 60 as by means of a force pump, thereby materially departing from such processes now in general use based largely upon the fractional distillation methods.

Referring now to the drawings in which 65 the apparatus is shown diagrammatically, there is provided a main supply tank 5 having an outlet to which is connected a pump 6 adapted to force the crude oil into a furnace or retort 7. This retort is provided at 70 one side with a heating coil 8 of relatively small diameter piping and comparatively great length, preferably of one inch diameter and one hundred and fifty feet in length, through which the crude oil is rapidly 75 forced by the pump 6 and exposed to a temperature of about 400° to 450° F. from whence it passes under approximately 100 pounds pressure to a jacketed heater 10 which is maintained at a temperature of 80 about 800° to 900° F. by means of superheated steam produced by coils 11 within the retort 7. It is to be noted that prior to the entrance of the oil from the coil 8 to the jacketed heater 10 a small part, approximately 10%, of superheated steam is injected into the oil conduit at the injector 12 which materially aids in increasing the temperature to the desired point as it passes 85 through the jacket.

After leaving the jacketed heater 10 the oil is passed through an expansion drum 13 provided with a spiral or helix 14 adapted to give the oil a whirling centrifugal and rectilinear movement. In other words, the oil 95 which is really in the form of a vapor, due to the high pressure and temperature to which it is subjected, is forced to circulate or rotate very rapidly and as it is traveling at the rate of approximately 100 feet per 100 second, the heavier parts of the vapor are forced outwardly from the center of the conveyer and exposed to the hottest temperature within the retort 7. The gas or lighter parts of the vapor stay nearer the 105 center of the screw or helix and consequently a more uniform breaking of the oil as it passes through the member 13 will re-

sult, thus making a very much larger percentage of light gas from raw oils than if said oils were simply passed through pipes or heated in a still. From the expansion 5 drum 13 the fluid mass passes to a pressure drum 15 where all carbon and deposits are allowed to settle before the fluid continues to a cooler 16 where the temperature is reduced to approximately 300° F.

10 After leaving the coil within the cooler the oil, gas and vapor obtained from the original oil passes to a separator 17 which is heated by superheated steam entering through the pipe 18 connected with the upper end of the steam jacket 10. At this point the temperature is raised to approximately 350° F. and all oil that will vaporize at this temperature passes through a pipe 20 to a condensing coil 21 maintained at a 20 temperature of approximately 350° F. All of the oil that will not vaporize at this higher temperature is pumped from the separator 17 through pipe 22 by means of pump 23 back to the tank 5 where it is again 25 forced through these steps of the process.

The oil, or benzin as it now may be called, is delivered from the condenser 21 to a temporary tank 24, thence forced rapidly through a steam jacketed heater, 25, Fig. 30 1^a, by means of steam pump 26, then through a second steam jacketed heater 27 into a steam still 28 maintained at a temperature of approximately 345° F. by means of steam admitted thereto by pipe 30 which 35 connects with the pipe 31 leading from the superheater coils within the retort 7. All oil vaporizing at 345° F. passes from this still to a condenser 32 and thence into storage tank 33. Any residue remaining in the 40 still 28 is drawn off by means of pump 34 and delivered to tank 35 from which point it may be drawn off and passed through the first or second steps again, as desired.

It is of course to be understood that the 45 apparatus which is shown largely diagrammatic is provided with the necessary valves, pyrometers, controlling and power means as may be necessary to effectively and continuously carry on the process; for instance the pumps may be economically driven by steam from the system shown.

From the above description, it will be seen that the process relates largely to a method of breaking down the heavy oils into lighter ones by subjecting the oils to a relatively high temperature and pressure as well as to a centrifugal motion while moving at a high rate of speed. The heavy oils are first put through a superheater and heated to the vaporizing point and thence conducted to a helical drum or conveyer within the furnace or retort where they are exposed to a much higher temperature according to the vaporizing point of the raw oils. As it passes through the drum as

above explained the heavier portions are forced by the centrifugal action to the outer surface of the drum, where they are subjected to the highest temperature. If all of the oil were simply passed through a series of pipes or heated in a still, it would be necessary to raise the temperature to such a high degree that a large part of the oil would carbonize. This objection is avoided by the present process in which no carbon 75 results, and only such parts of the oil that will stand the heat are subjected to high temperatures.

The present invention is therefore believed to be simple and practical in operation, reliable and highly efficient in use and inexpensive to carry out. In fact, the invention is believed to accomplish, among others, all of the objects and possess all the advantages herein set forth. 80

Without further analysis, the foregoing will so fully reveal the gist of this invention that others can by applying current knowledge readily adapt it for various applications without omitting certain features 90 that, from the standpoint of the prior art, fairly constitute essential characteristics of the generic or specific aspects of this invention, and therefore such adaptations should and are intended to be comprehended within the meaning and range of equivalency of the following claims. 95

I claim:

1. The herein described method of treating oil which includes the step of vaporizing oil at a temperature of approximately 1000° F. and simultaneously causing said oil to traverse a helical path at the rate of not less than approximately 100 feet a second. 100

2. The herein described method of treating oil which consists in the steps of heating the oil to approximately 400° F., mixing the same with a small per cent. of steam at high pressure and subsequently exposing the mixture to a temperature in the neighborhood of 1000° F. while being simultaneously subjected to a whirling and rectilinear movement at a rate of speed not less than approximately one hundred feet per second. 105

3. The herein described method of treating oil which consists in the steps of heating the oil to approximately 400° F., mixing the same with a small per cent. of steam, exposing the mixture to a temperature in the neighborhood of 1000° F. and 110 simultaneously subjecting the mixture to a rotative rectilinear movement under high pressure whereby the mixture travels through a helical rectilinear path at not less than approximately 100 feet a second.

4. The herein described method of treating oil which consists in the steps of forcing oil under relatively high pressure rapidly through a coil heated to approximately 400° F., subsequently increasing the tem- 130

perature of the oil to approximately 1000° F. and while still under great pressure, forcing the oil vaporized at that temperature through an elongated helical drum at 5 a rate of speed not less than approximately one hundred feet per second.

5. The herein described method of treating oil which consists in forcing the oil rapidly through a coil heated to approximately 10 400° F. and subsequently increasing the temperature to above 1000° F. to vaporize the oil and simultaneously forcing the oil vapor in a helical rectilinear path at not less than approximately 100 feet a second, allowing the oil vapor to cool and settle prior 15 to a re-heating at a temperature of approximately 350° F., at which point the volatilizable and non-volatilizable oils are separated.

6. The herein described method of treating oil which consists in heating the oil to 20 approximately 400° F., mixing the oil with a small per cent. of steam, giving the mixture a helical rectilinear movement under high pressure and at a speed not less than 25 approximately one hundred feet per second through a helical drum heated to about 1000° F., conducting the vapors to a condenser, and subsequently conducting the non-vaporizing oil back to the starting point.

30 7. The herein described method of treating oil which consists in heating the oil to a vaporizing temperature while simultaneously being subjected to a helical rectilinear movement under great pressure and at a 35 speed not less than approximately one hundred feet per second, allowing the oil vaporized at a definite temperature to pass into a condenser, conducting the non-vaporized oils back to the starting point, collecting the condensed vaporized oils and re-heating them to approximately 345° F. in 40 a still which permits the volatilized oils to be collected in a condenser and the non-

volatilized oils to be conducted to a point for re-treatment. 45

8. The herein described method of treating oil which consists in passing the oil through a coil within a retort heated to approximately 400° F., mixing the heated oil with approximately 10% of superheated 50 steam at approximately 100 pounds pressure, heating said mixture to a point above 1000° F. subsequently subjecting the mixture to a very rapid rectilinear and helical movement and at a speed not less than approximately one hundred feet per second, passing the vapors to a pressure drum where the mixture is allowed to settle, separating the vaporizable oils from the non-vaporizable oils, and treating the former to a 55 fractional distillation step while the latter is returned to the starting point.

9. The herein described method of treating oil which consists in forcing oil through a relatively small pipe at great speed and 60 exposing the same to a temperature of approximately 400° F., adding a small per cent. of superheated steam and subsequently heating said mixture in an expansion drum to approximately 1000° F. whereby the mixture is vaporized, subsequently forcing said vapors in a helical rectilinear path and at a speed not less than approximately one hundred feet per second, cooling and then re-heating the vapors to a critical point at 65 which temperature the vaporizable oils are thence conducted through a fractional distillation step while the non-vaporizable oils 70 are returned for treatment.

In testimony whereof I affix my signature 75 in presence of two witnesses.
